1

This invention relates to an electrical apparatus and particularly to sign utilizing a luminescent medium such as a luminescent gas or vapor or mixture thereof, generally referred to in the trade as neon signs.

In accordance with the invention, there is provided a plurality of pre-fabricated letters or indicia, each one of which consists of glass or similar sealed tubing containing the usual neon sign filling of gas and/or vapor or mixture thereof. Each sign element or indicia is free of any lead-in electrodes. The glass sign elements are preferably provided with suitable means for temporarily or permanently anchoring the same to a sign support. This support may consist of any desired mechanical structure strong enough to support the weight of the sign elements. The support includes as a part thereof a high frequency tank circuit in the form of a plurality of conductors. The high frequency tank circuit cooperates with the sign elements to induce a gaseous discharge within said sign elements in a manner well known in the gaseous conduction art.

The use of a high frequency vacuum tube type of oscillator for energizing the sign elements provides a construction which has a peculiar advantage as far as blinking a sign is concerned. In conventional neon sign installations, thermostatic switches or motor-driven interrupters are necessary to flash the sign on and off at regular intervals. With a high frequency oscillator, it is possible to incorporate, within the circuit, simple control means whereby the oscillator blocks periodically. Thus, the effect on the sign is to switch the same on and off at regular intervals.

A structure embodying the invention is preferably so designed that the frame work of the sign, this being the stationary portion thereof upon which letters or indicia are supported, consists of conducting material such as iron, steel, aluminum, copper and like conducting materials in perforate or imperforate sheet form. These conductors function as electrical conductors for high frequency currents. In accordance with the present invention the ferromagnetic conducting materials are preferred. It is preferred to design the frame so that ample surface for conducting the high frequency currents is provided. Thus, the ohmic resistance of the frame to the high frequency currents may be reduced to a negligible value.

In the practice of the invention, opposed conducting sheet metal electrodes generally in one

2

plane have cooperating edges to define an insulating gap. Cooperating with such electrodes are sign elements so disposed as to lie in intense electric fields. It follows that every sign element must be disposed so as to extend across the gap. Due to the skin effect at high frequencies, the field pattern may generally extend to the outer edges of the electrodes. So long as a sign element is disposed in proximity to the opposing electrode surfaces and lies within the projected outline of the electrodes, it will be subjected to electric fields.

I have discovered that, if the gap in air between opposing edges of sheet metal conducting electrodes has a transverse dimension of less than about three-fourths of an inch, for frequencies below about one hundred mega-cycles, for example, remarkable operating efficiency and freedom from radiation result. The minimum gap separation in air may be of the order of one sixty-fourth of an inch, although this minimum distance will vary within fairly wide limits depending upon such conditions as break-down potential of the atmosphere, atmospheric conditions, the dirt and soot content of the atmosphere, the transverse electrode dimensions, operating frequency and the like. The maximum gap dimension in air is of the order of three-fourths inch. The preferred gap dimension is from one sixty-fourth to three-eighth inch. It is to be understood that the term "transverse dimension" indicates a dimension normal to the electrode edges at a particular gap region under consideration. As will be apparent later, the transverse dimension of the electrodes is not necessarily coincident with the geometrical width thereof.

It is understood that any dielectric medium may be used as the seat of the electric fields incident to the flow of currents along the surfaces of the sheet electrodes. In accordance with well-known theory, the potential gradients established in such dielectric materials is a function of the dielectric constant. It, therefore, becomes apparent that, where other materials than air are used as a dielectric medium, the critical electrode spacing will have to be correspondingly adjusted. In general, however, unless materials having high dielectric constants are used, the gap dimensions previously given may be utilized.

The sign elements themselves must be disposed in sufficiently close proximity to the sheet electrodes so that an intense electric field will pass through such sign elements. Inasmuch as the electric field intensity drops off inversely as the

square of the distance from the electrode surface, efficient operation requires close disposition of the sign elements to the electrode surface.

It has been found that a well-designed structure making full use of the invention herein provides a neon sign requiring comparatively low power equipment and is remarkably free from radiation. Signs having a total of as much as fifteen or twenty linear feet of luminescent gas column may be efficiently energized by oscillators equipped with low power vacuum tubes generally classed as receiving tubes. Thus, an oscillator having a radio frequency output of around two watts is ample for energizing a neon sign of the size previously given. Such an oscillator, when operating at a radio frequency of less than thirty mega-cycles will have negligible field intensity at a distance of 300 feet, as presently required by governmental regulation.

The simplest embodiment of the invention utilizes a disposition of sheet metal electrodes in one general flat plane. However, the electrodes may be curved out of a flat plane or may be disposed in parallel planes. The sole limitation is that the electrodes should have no common projected surfaces along their faces. Thus, sign elements may be disposed across the gaps and over-lie the electrode area rather than lie in the gap between electrodes or lie across the gap and beyond the outer edges of the electrodes. The sign elements in a simple form may generally lie in flat planes. However, it is possible to curve them, such curvature being normal to the line of sight.

The sign elements themselves may be fastened to the sign structure, either temporarily or permanently, in any desired manner. Conventional fastening means as by flexible or rigid clamps or tierods may be relied upon. However, a simple means for maintaining the sign elements in position makes use of permanent magnets. Thus, the sign elements may carry small blocks of material such as Alnico, each of which is magnetized and cooperates with ferromagnetic sheet metal electrodes. It is, of course, possible to reverse the relative locations of the permanent magnets and ferromagnetic material or use permanent magnets on both the sign elements and frame.

In order to fully utilize the flexible characteristics of the sign with regard to change in indicia, it is possible to utilize simple indicia elements, some of which are straight and some of which are curved, and combine these to form complete letters. It is, thus, possible to build a sign of any desired size and showing any desired matter from a number of simple elements.

Each sealed element must have a substantial portion thereof disposed in the radio frequency field between opposed electrodes in order that gaseous conduction shall occur. To this end, it is preferred to shape the gap forming opposing electrode edges so that every sign element will have at least one portion thereof extending from one electrode across the gap to the other electrode. For ordinary purposes, a zig-zag arrangement suitably proportioned with respect to the height and width of proposed letters and sheet metal electrodes may be provided. Other tortuous or non-linear shapes for opposed electrode surfaces may be devised, depending upon the type of letters or the shape of sign indicia.

For a more thorough understanding of the invention, reference will now be made to the drawings showing exemplary embodiments of the invention. It is understood, however, that various

changes in the structure and lay out may be made to suit varying conditions and requirements.

Figure 1 shows a perspective view of a sign with a portion broken away and illustrating one form of the invention.

Figure 1a is a sectional detail on line 1a-1a of Figure 1.

Figure 2 is a diagrammatic view of a modified form of sign and showing an oscillator circuit.

Figure 3 is an elevation view of a sign and diagrammatic view of an oscillator circuit illustrating a preferred modification.

Figure 4 is a sectional end view on line 4-4 of Figure 3.

Figure 5 is a perspective sectional view of a sign and a diagrammatic showing of an oscillator circuit of a still further modification.

Figure 6 is a top view of the sign of Figure 5 but showing the sign in complete form.

Figure 7 is a perspective detail of one end of the sign of Figure 5 showing electrode adjusting means.

Figure 8 is an elevation with certain parts broken away and in section illustrating a further modification of the invention.

Figure 9 is a sectional detail on line 9-9 of Figure 8.

Referring first to Figure 1, the sign proper comprises flat members 10 and 11, preferably of sheet metal such as iron or steel. These members may have any desired length and are shown as being of rectangular shape for simplicity. Flat members 10 and 11 have opposing edges 12 and 13 separated by an insulating gap 14. Gap 14 may consist either of air or of any suitable solid insulating material. Sheet members 10 and 11 have curled or enlarged edges 16 and 17, these being formed in any suitable manner such as by rolling. Edges 16 and 17 are adapted to ride in suitable grooves 18 in support members 19 and 20. Support members 19 and 20 may be either of insulating or conducting material.

Support members 19 and 20 may be rigidly maintained in spaced relationship at one end by support wall 22. This support wall is here shown as forming part of a box 23, although this is unnecessary to the invention. Support members 19 and 20 at the free end are maintained rigidly in predetermined relation by hinged end member 24. Wall 22 and end member 24 are suitably insulated from members 19 and 20 or may be formed of insulating material such as wood, glass or the like.

End member 24 is hinged for a purpose which will be apparent later. Support members 19 and 20 are so shaped as to provide troughs 25 and 26. Disposed over flat members 10 and 11 is sheet 28 of any insulating material. Thus, a thin sheet of rubber, wood or any other insulating material may be disposed in troughs 25 and 26. Sheet 28 may be omitted. Thus, sheet steel members 10 and 11 may be utilized without any covering, or the surfaces of these flat members may be insulated by varnish or paint. However, in many instances, it may be desirable to provide a suitable background for the sign letters, which background may be formed as an insulating sheet.

Pre-formed and pre-fabricated sign letters 39 may be disposed between support members 19 and 20. In the simple construction shown in Figure 1, these sign elements are maintained in position by being so dimensioned as to extend into troughs 25 and 26. It is understood that the sign elements may be removed by opening

end member 24 and sliding the letters out. Other means for maintaining the letters in position may be used as illustrated in certain other modifications.

It will be noted that each of the sign elements 30 extends across insulating gap 14. As has been pointed out before, insulating gap 14 is small as far as transverse dimensions are concerned and, in air, would be between about one sixty-fourth and three-quarters inch. The transverse gap dimension does not necessarily have to remain uniform along the gap length.

Box 23 may contain any suitable source of radio frequency potentials such as a simple oscillator. Sheet metal members 10 and 11 are connected to the oscillator so that a difference of radio frequency potential may be imposed across insulating gap 14.

With suitable frequency and power, the letters will have a discharge induced therein to render the gas and/or vapor luminescent.

Referring now to Figure 2, electrodes 35 and 36 are shown. These electrodes are shown in diagrammatic form and no attempt to show proportions or dimensions has been made. Thus, electrode 35 has a branch 35' extending on the other side of electrode 36 so that electrode 36 is disposed between two arms of one electrode. Electrodes 35 and 36 are connected to terminals 37 and 38 of an inductance 39. Inductance 39 has intermediate point 40 connected by lead 41 to winding 42 of transformer 43. Point 40 may be varied to insure proper matching of the sign elements load to the oscillator. Transformer 43 has primary 44 energized by any suitable source of alternating potential. Transformer 43 has filament winding 45 connected by leads 46 and 47 to filamentary cathode 48 of vacuum tube 49. Tube 49 has control grid 50 connected through suitable grid resistor 51 back to the cathode. Control grid 50 is also connected through blocking condenser 52 to terminal 37 of inductance 39. Vacuum tube 49 has anode 53 connected by lead 54 to terminal 38.

Transformer windings 42 and 45 have a common connection to lead 47. It is understood that winding 42 furnishes sufficient potential to energize the anode circuit of tube 49.

The circuit shown in Figure 2 is one form of a simple oscillator which may be used to energize electrodes 35 and 36. Other forms of oscillators may be used, it being understood that the frequency is adjusted to have a value desirable for sign operation. Sign elements 56 may be disposed across the electrode structure. In the form shown in Figure 2, each sign element lies across two insulating gaps. Thus, one gap 57 is formed between electrode 35 and electrode 36. The other gap 58 is formed between electrode 36 and electrode 35'. In actual practice, electrodes 35, 35' and 36 will have a substantial area with gaps 57 and 58 being small, of the dimensions set forth above, in comparison to such area. It is clear that the sign construction shown in Figure 1 may be modified in view of Figure 2 to provide two gaps instead of the single one. Also, a single letter may extend across one gap only.

Referring now to Figure 3, a modified sign structure is shown wherein an irregular shaped insulating gap is utilized. By proper shaping of the gap, it is possible to devise such a gap as will permit of satisfactory disposition of various sign elements over the electrodes in a manner so

that each sign element crosses the gap. Thus, specifically referring to Figure 3, sheet metal electrodes 60 and 61 are provided. Electrodes 60 and 61 have opposing gap defining edges 62 and 63. These edges define gap 64 having the outline shown as one example. Thus, as shown, gap 64 has a straight portion 65 followed by a plurality of substantially V-shaped portions 66 and terminating in straight portion 67. Portion 66 need not necessarily be straight or form a V. If desired, these portions may be irregular or may define a regular cyclic curve, such as a sine wave, for example. It is to be understood that electrodes 60 and 61 are endowed with sufficient strength so that portions defining the gaps will be satisfactorily supported.

Means may be provided for adjusting the transverse gap dimension. A simple means, shown in detail in Figure 4, consists of bosses 70 and 71 carried by electrodes 60 and 61. The spacing between bosses may be controlled by bolt 72. Bolt 72 threadedly engages boss 71 and is loose in boss 70. Rubber pad 73 between the bosses is provided to maintain the separation.

Straight portions 65 and 67 of the gap may be provided at spaced intervals along the sign as a whole if the sign length is great and if such straight portions are desired. It is also possible to provide bosses 70 and 71 and adjusting bolt 72 at intermediate places along the sign length.

The surface of electrodes 60 and 61 may be covered with any suitable sheet insulating material as previously disclosed. It is preferred in this particular instance to have electrodes 60 and 61 of some ferromagnetic material such as sheet iron or sheet steel. The ferromagnetic property of this material is utilized for retention of sign elements.

Cooperating with electrodes 60 and 61 are sign elements 75. These sign elements may take on elemental shapes, such as straight lines or simple letters. As an example, the letter H may be formed of three sign elements. Each sign element consists of a simple sealed glass envelope having any desired gas or mixture of gases or vapors at any desired pressure. The sign elements are cemented or joined together to form a composite sign element, in this instance letter H, although they need not be. The cementing or joining of the sign elements into a letter or indicia before attaching them to the sign is preferred.

Additional sign elements may be formed, such as 76, in the shape of P. Sign element 77, having the curved shape shown may cooperate with sign element 76 to change the P to B. It is evident that innumerable combinations of different shapes of sign elements may be utilized to form different letters, numerals or sign indicia in general.

The length of each sign element and the shape and character of the gap are so proportioned that every sign element crosses the insulating gap at least once. The outline of the entire insulating gap is, obviously, subject to innumerable modifications, depending upon the size, character and disposition of the sign elements and the desired composite elements.

Electrodes 60 and 61 may be energized in any suitable fashion. Thus, a diagrammatic oscillator circuit is shown generally similar to the circuit of Figure 2. Power transformer 43 in Figure 2 is modified to provide an auto-transformer 78. In addition, grid resistor 51 is variable.

As is well known in the art of blocking oscillators, it is possible to provide sufficiently high grid resistance so as to prevent continuous oscillator operation. The oscillating system may then operate for a certain period of time and become blocked. During the blocking, the charge in blocking condenser 52 gradually dissipates and permits renewed oscillator operation. By controlling the time constant of condenser 52 and resistor 51, it is possible to control the "on" and "off" time of the oscillator. A simple neon sign 10 flasher may thus be provided.

The various sign elements may be retained on electrodes 60 and 61 in any desired fashion. It is possible to maintain the composite sign elements in position in Figure 3 by simple mechanical retention, as illustrated in Figure 1. However, a modified retaining means is provided and serves to endow the sign with substantial advantages. Each sign element or composite sign 15 elements may have cemented thereto one or more blocks 78 of permanent magnet material. The well-known family of alloys of which Alnico is an example may be used. Such blocks are cemented or otherwise permanently fastened to sign elements 75 or 76, as the case may be, and cooperate with ferromagnetic electrodes 60 and 61. The force of attraction due to Alnico may be sufficiently great to maintain a sign element 20 strongly in position without requiring excessively large blocks of metal. In general, it is preferred to dispose the permanent magnet blocks so that they will not lie across an air gap. However, the precise disposition of the magnetic blocks is of no importance and may be varied within wide 25 limits. The blocks may be disposed between a sign element and electrode surfaces as shown in Figure 4, or the blocks may extend laterally of a sign element as shown in Figure 5. In the latter case, the sign element may be closer to the electrode surfaces.

The means for adjusting the width of the air gap may be relied upon to control the character 30 of the load imposed upon the oscillator. In this way, the radio frequency potential and frequency may be controlled within substantial limits. With variation in the number of sign elements on the electrodes and thus a variation in load, it may be necessary to vary the gap to maintain a pre-determined frequency.

Referring now to Figures 5 to 7, inclusive, a 35 still further modification is shown. Elongated insulating blocks 80 and 81 may support an electrode structure as shown. Thus, insulating block 80 may have a U-shaped sheet iron electrode 82 enclosing a portion thereof. Similarly, block 81 may have U-shaped electrode 83 enclosing the same. Between electrodes 82 and 83, there may be disposed at least one, or more if desired, plain electrodes 84. It is understood that both sides 40 of the sign are the same. As shown, insulating gaps 85 and 86 are provided between the various electrodes on opposite sides of the sign. Gaps 85 and 86 are shown as straight, for simplicity, but may assume the general shape of gap 64 illustrated in Figure 3, and are formed by projecting strips from insulating blocks 80 and 81.

As shown in Figure 7, each insulating block 45 has boss 88 cooperating with bracket 89 carried by one of the U-shaped electrodes. The boss and bracket have bolt 90 for adjusting the transverse dimension of the gap. As shown in Figure 7, bolt 90 may conveniently turn idly in bracket 89 but threadedly engages boss 88. By suitable construction of bolt 90, such as by under-cutting, it 50 will be evident that the spacing between the boss 55 and bracket may be maintained without the necessity of any elastic separating means.

Sign elements 92 may be disposed over various portions of the sign. Letters L and W are shown by way of example, these being provided with permanently magnetized blocks 94 extending laterally from the sign elements. On the other hand, letters C and O are shown as being mechanically supported by straps 95 going over the top of the sign. While the sign elements are shown as forming complete letters, it will be understood that each letter may be a composite sign element such as described in connection with Figure 3.

The oscillating system for energizing the sign 55 comprises vacuum tube 100. This vacuum tube may be any one of a number of types of tubes. As shown here, this vacuum tube has a plurality of sets of electrode assemblies such as a diode and tetrode. The system described herein is particularly adapted for universal operation on either alternating or direct current. For 110 volt work, a type 117 tube may be used for moderate loads. Thus, tube 100 has heaters 101 and 102 in series across 110 volt lines 103 and 104. Cooperating with these heaters are cathodes 105 and 106. Cathode 105 is connected through condenser 107 to line wire 103. Cooperating with cathode 105 is anode 108 connected to line wire 104.

Cathode 106 is connected by wire 110 to line 60 wire 103. Cathode 106 is also connected by grid resistor 111 to lead 112 going to control grid 113 cooperating with cathode 106. Lead 112 is connected through blocking condenser 114 to terminal 115 of inductance 116. Inductance 116 has intermediate point 117 connected by lead 118 back to rectifier cathode 105. Lead 118 is also connected to accelerating electrode 119 of the tetrode. The tetrode has anode 120 connected by lead 121 to terminal 122 of inductance 116. The 65 output of the system is taken at terminals 115 and 122. Thus, terminal 115 is connected by a lead to center electrode 84, while terminal 122 is connected by leads to end electrodes 82 and 83.

Upon application of direct current, assuming 70 that line wire 104 is positive to line wire 103, it will be clear that the rectifier and tetrode will be connected in series. The circuit goes from line wire 104 through the diode to lead 118 to tap 117 thence through a portion of inductance 116 to terminal 122. From 122, the direct current circuit continues to anode 120 through the tetrode to cathode 106 thence to line wire 103. At the same time, accelerating electrode 119 will be raised to a suitably high potential. On alternating current, the diode will suppress negative portion of each cycle and permit the system to operate at those portions of the cycle when line wire 104 is positive to line wire 103.

As far as the generation of oscillations is concerned, the circuit shown is a conventional oscillator and a detailed description of the operation thereof may be found in any standard reference book.

Referring now to Figure 8, a sign having substantial vertical dimensions is disclosed. This permits the use of a substantial series of vertically arranged letters or individual large letters. In this particular modification, electrodes 130 to 75 136 inclusive are provided. These electrodes may be of any suitable conducting material such as sheet iron, as previously indicated. As shown, electrodes 130 to 133 inclusive and 136 are of simple rectangular shape and provide a simple linear insulating gap between them. Electrodes

.134 and .135 are shaped to provide a gap generally similar to that shown in Figure 3. Thus, electrodes .134 and .135 provide gap .138. Gaps between adjacent electrodes may be formed by flexible insulating material .140. Such material may consist of rubber or any other elastic material. The rubber may extend throughout the full extent of the gap or merely at the ends of the electrodes near the sides thereof.

As shown in Figure 8, electrodes .130 to .136 are disposed so that they all lie in one general plane and, when vertically mounted, would appear as shown. The electrodes are maintained in aligned relationship by suitable supporting means. Thus, simple U-shaped members .142 are provided at the opposite sides of the electrodes. U-shaped supporting means .142 may have insulating block .143 within which the electrode edges may move. A bottom supporting member .144 is provided upon which the stack of electrodes is supported. Any suitable clamping means, such as screw .146, may be provided at opposite sides of the sign to adjust the transverse dimensions of the various gaps. By disposing live rubber between adjacent electrodes, it is clear that any desired relationship between gaps may be maintained while adjusting the dimensions thereof. Thus, the gaps may be equal, or some gaps may be wider than others.

The entire surface of the electrodes may be covered by insulating sheet .148 of any suitable material. Suitable sign elements may thereupon be disposed in various portions of the sign, such sign elements being retained in position either by the magnetic means disclosed in Figures 3 and 5, or by any suitable mechanical means. It is understood that the electrodes are so wired as to provide for a potential difference across any gap, such potential difference being supplied by any suitable oscillator. Inasmuch as the electrical connections for the various electrodes will be obvious to anyone skilled in the art, no detailed showing need be made. It is understood that electrodes .130, .132, .134 and .136 may either be connected in parallel with the remaining electrodes also connected in parallel and of opposing polarity or, in the alternative, electrodes .130 and .136 may be connected to the oscillator with the intervening electrodes forming a series cascaded arrangement.

It is understood that the insulating gaps in the various modifications shown will have transverse dimensions of the order previously given, namely between about one sixty-fourth and three-fourths of an inch. In general, the transverse dimensions will be a function of the nature of the insulating material, such as air or solid material, the desired operating frequency, the physical dimensions of the sign elements, the amplitude of the radio frequency potentials, the extent and nature of the medium extending between the electrodes at the gaps on the one hand and the interior of the sign elements where ionization is to be effected on the other. It is well known that the dielectric constant has a profound effect upon the nature of the potential gradient existing between two electrodes. In a structure having a number of different dielectric media, the dielectric constant of one medium will affect the potential gradients in the remaining dielectric media. It is, however, comparatively simple to adjust the operating frequency of the oscillating system including the work circuit. Recourse may be had to tuning capacitors or conductors for supplementing or correcting any departures from predetermined circuit constant occasioned by varia-

tions in gap dimensions or variations in structural materials. In any event, the transverse dimension of a gap should be small enough so that the electric field intensity is sufficiently high to induce satisfactory luminescence in the sign elements.

The length of the gaps may be made as great as necessary. It is clear that a structure having a long gap and supporting a large number of sign elements will require an oscillator having substantial power output. Such considerations, however, are well known in the electronic art and need no extended discussion.

The amplitude of radio frequency potential for proper sign operation may be adjusted by increasing the same till proper illumination is effected. It is impossible to state definitely what particular amplitude of radio frequency potential is necessary. The amplitude itself is dependent upon the nature of the gas within which a discharge is to occur, the frequency, the electrode shape, physical distances between electrode surface and sign elements, the reactance of the circuit components, the quantity of residual ions in the sign elements and other obscure factors. The simplest and most practical procedure is to adjust the amplitude to a level giving desirable operating conditions. The adjustment of such amplitude is a matter well within the skill of any man in the electronic art and needs no description.

While the mechanical sign structures have been illustrated as flat, it is evident that they may be bent to lie in curved planes or irregular planes.

I claim:

35. 1. A neon type sign comprising a support including at least two spaced electrodes defining a gap, therebetween of between about $1/64''$ and about $3/8''$, each of said electrodes having a projected outline having the dimension transverse to the gap large in comparison to the gap dimension, said electrodes being adapted to be energized by high frequency electric currents with a radio-frequency difference of potential existing across said gap, at least one sealed transparent envelope containing an ionizable medium at a reduced pressure, said envelope being free of metallic electrodes and said medium being adapted to be excited to luminescence by said high frequency field, and means for maintaining said envelope substantially in contact with said electrodes and extending across said gap, said envelope lying approximately within the projected outlines of the electrodes.

55. 2. In combination, a vacuum tube oscillator, and neon type sign comprising a support including at least two spaced electrodes defining a gap therebetween of between about $1/64''$ and about $3/8''$, each of said electrodes having a projected outline having the dimension transverse to the gap large in comparison to the gap dimension, means for feeding the output of said oscillator to said electrodes to generate a radio frequency difference of potential across said gap, at least one sealed transparent envelope containing an ionizable medium at a reduced pressure, said envelope being free of metallic electrodes and said medium adapted to be excited to luminescence by said high frequency field, and means for maintaining said envelope in proximity to said electrodes across said gap, said envelope lying approximately within the projected outline of the electrodes.

65. 3. The neon sign according to claim 2 wherein said gap is tortuous.

70. 4. The neon sign according to claim 2 wherein 75 said vacuum tube oscillator is of the blocking type

11

and is adapted to go on and off intermittently for blinking said sign.

5. A neon type sign comprising a support including a plurality of spaced electrodes defining a gap therebetween of between about $1/64''$ and about $\frac{1}{8}''$, each of said electrodes having a projected outline having the dimension transverse to the gap large in comparison to the gap dimension, means for impressing a high frequency potential on said electrodes to provide a radio frequency difference of potential across each gap, at least one sealed transparent envelope containing an ionizable medium at reduced pressure, said envelope being free of metallic electrodes and said medium being adapted to be excited to luminescence by said high frequency field, said envelope being large enough to extend at least across one gap for substantial distances from said gap in a direction transverse to the gap, and means for maintaining said envelope in proximity to said electrodes and across said gap, said envelope lying approximately within the projected outline of all of the electrodes.

6. The sign according to claim 5 wherein resilient means are provided for maintaining adjacent electrodes in position to define said gaps and wherein means are provided for compressing said resilient means and adjusting the transverse dimension of all gaps simultaneously.

7. A neon type sign comprising a support including at least two spaced flat electrode surfaces, means for maintaining said surfaces so that they lie in one plane with the edge of one surface opposing an edge of the other surface to define a gap therebetween of between about $1/64''$ and about $\frac{1}{8}''$, said electrode surfaces having dimensions transverse to the gap large in comparison to the gap dimension so that the electrode area is large in comparison to the gap area between edges, means for impressing electric currents on said electrode surfaces at a radio frequency to develop a radio frequency difference of potential across said gap, at least one sealed transparent envelope containing an ionizable medium at a reduced pressure, said envelope being free of metallic electrodes and generally lying in a flat plane, and means for maintaining said envelope against said electrode surfaces and

10

12

across said gap, said envelope lying within the projected outline of the electrodes and gap surfaces and extending for substantial distances along said surfaces from said gap.

8. A neon type sign comprising a support including at least two spaced electrode surfaces, means for maintaining said surfaces so that an edge of one surface opposes an edge of the other surface to define a gap therebetween of between about $1/64''$ and $\frac{1}{8}''$, said electrode surfaces having dimensions transverse to the gap large in comparison to the gap dimension so that the electrode area is large in comparison to the gap area between edges, said electrode surfaces being adapted to be energized by high frequency electric currents with a radio frequency difference of potential existing across said gap, at least one sealed transparent envelope containing an ionizable medium at a reduced pressure, said envelope being free of metallic electrodes and said medium being adapted to be excited to luminescence by said high frequency field, and means for maintaining said envelope in proximity to said electrode surfaces and extending across said gap, said envelope lying approximately within the projected outline of the electrode and gap surfaces.

WILLIAM J. BROWNER.
